POWER TRANSMITTER OR SIMILAR ARTICLE

Stratis George Belezos, Canton, and Orfeo J. Salvucci, Holbrook, Mass., assignors to The Murray Company of Texas, Inc., Dallas, Tex., a corporation of Delaware

Filed Nov. 5, 1965, Ser. No. 82,489

Term of patent 14 years

(Cl. D55—1)

FIG. 1 is a front elevation of a power transmitter or similar article showing our new design;

FIG. 2 is a rear elevation of the device of FIG. 1;

FIG. 3 is an end elevation from either end of FIG. 1;

FIG. 4 is a plan view of the device of FIG. 1; and

FIG. 5 is a bottom view of the device of FIG. 1.

We claim.

The ornamental design for a power transmitter or similar article, substantially as shown.
